UNITED STATES PATENT OFFICE.

MARGARET KILLEEN, OF HALIFAX, CANADA.

COMBINED WASHING AND WRINGING MACHINE.

SPECIFICATION forming part of Letters Patent No. 552,842, dated January 7, 1896.

Application filed July 28, 1894. Serial No. 518,903. (No model.)

To all whom it may concern:

Be it known that I, MARGARET KILLEEN, a subject of the Queen of Great Britain, residing at Halifax, in the Province of Nova Scotia, Dominion of Canada, have invented a new and useful Improvement in a Combined Washing and Wringing Machine, of which the following, in connection with the accompanying drawings, is a full, clear, and exact description.

My invention relates to washing and squeezing or wringing machines of the washboard type of construction; and my improvements will be fully understood from the accompanying specification and claims in connection with the drawings.

By my improvements I am enabled to furnish the public with a cheap, simple, and convenient washboard-like washing and wringing contrivance, with which the operation of washing may be performed by the aid of mechanical means, or both washing and wringing may be performed by the aid of such means, or the operation of hand-washing and mechanical wringing may be performed by the aid of such means, and the said machine can be used in the ordinary washtub or other like water-containing vessel.

In the accompanying drawings, which form a part of this specification, Figure 1 represents a perspective view of my improved contrivance; Fig. 2, a vertical longitudinal section of the same.

11 in the accompanying drawings designate two standard-like side-supporting pieces of a stationary washboard, and 13 rollers forming the rubbing-bed 13^a of the same. The lower ends of the side pieces are suitably shaped to rest, when desired, upon the bottom of an ordinary washtub, and thus allow of the contrivance being used in such tub or other suitable water-holding vessel. On the back of the standard-like side pieces spring-clips 9 are provided for taking hold of the upper edge of the tub and thereby holding the contrivance steady when in use.

The rollers 13 of the rubbing-bed 13^a are journaled in the side pieces 1, so as to be free to revolve and not bind upon one another, and these rollers are all about the same diameter, and unitedly form a long, continuous, but slightly-undulated scouring-surface. Im-

mediately above this roller-bed two wringing-rollers 2² are arranged close together. These rollers are of greater diameter than the rollers 13, and are also journaled so as to revolve in the side pieces 1 of the rubbing-bed 13^a. The upper roller is, as usual, held down by spiral springs 16, and the shaft of the lower roller is extended through one of the side pieces at one end, and on this extension a driving-pulley 7 is applied for revolving the lower wringing-roller and causing it to give motion to endless clothes-carrying belts 3 and adapting it for being used conjointly with the upper wringing-roller for wringing clothes that have been washed.

The rollers 2², as well as those of the roller-bed, are provided at their ends, inside the side pieces, with circumferential grooves for accommodating the endless carrying-belts and their appendages. The endless carrying-belts 3 are provided with spring-clips 3¹ and are applied around the rubbing-bed 13^a and the lower wringing-roller 2², and these belts, with their clips, during their movement are allowed uninterrupted freedom to travel in the said grooves of the rollers, while at the same time they are confined against lateral movement.

In front of the roller-bed 13 and the endless carrying belts a frame 4, provided with journaled and revolving rolls 4', is arranged to reciprocate. The side pieces of this frame are confined upon the side standard-pieces 1 by flat bars 6 whose ends are fastened to the side standard-pieces of the rubbing-bed 13^a, below and above the reciprocating frame, by adjusting-screws 10, on which the spiral springs 16, acted upon by nuts 8, are applied. The adjusting-screws, springs, and nuts serve as a means for keeping the rollers 4' of the frame 4 in close spring-contact with the rollers 13 of stationary rubbing-bed 13^a, and also for adjusting the pressure of the rollers 4' of the frame 4 upon the rollers 13 of the rubbing-bed 13^a, and thus a perfect rubbing action can be insured without injury to the clothes or other articles while being operated upon by and between the two beds. The arrangement of the flat bars 6 and the adjusting-screws is such that the frame 4 is allowed room to reciprocate to the extent required.

For operating the herein-described contrivance the following mechanism is provided:

At the top of the standard-like side pieces 1 a crank 12, having two bends or crank-arms between its ends, is applied, and on the outer or extended end of this shaft there is a pulley 5 7^a and a crank-handle 5. From the cranks or bends of the shaft 12 two loosely-connected pitmen 17 are extended and attached loosely to a cross-piece of the reciprocating-roller bed-frame 4, and by these means the said 10 roller bed-frame is reciprocated over the surface of the clothes when the crank-shaft is revolved. Thus connected, the frame 4 is adapted for being swung outward and upward, as illustrated in Fig. 2 by dotted lines, for 15 a purpose hereinafter stated. On an extended end of the lower roller of the rubbing-bed 13^a a pulley 7 is applied so that this roller may be revolved and thereby aid the wringing-roller 2^a in revolving the endless carrying-belts 3. The lower wringing-roller and the lower roller of the roller-bed 13^a are revolved by means of an endless belt 11, passed up from 20 the pulley 7 entirely around the pulley 7, then up diagonally to the pulley 7^a, partly 25 around said pulley, then diagonally to and in contact with pulley 7, and then down to pulley 7^a, where its ends are united. Instead of using a single belt passed about all the rollers, two belts may be used, one crossed and 30 the other straight. It will be observed that the lower wringing-roll and the lower roll of the roller-bed 13^a revolve while the reciprocating roller-bed is reciprocated, and thus, if desired, the clothes 35 when fully washed can at once be passed between the wringing-rollers by a slight direction given to the same by the human hands; or, if desired, they can be removed from the washboard-like contrivance without passing 40 them through the wringer. Again, if the clothes are not passed between the two roller-beds and are only gently rubbed upon the roller-bed 4^a, they can be conveniently passed 45 between wringing-rollers. When it is desired to get access to the stationary-roller bed-frame and its rollers, the reciprocating frame can be thrown up to the 50 position shown by dotted lines in Fig. 1 by removing the nuts and slipping the bars and springs off the screws.

In operating with the herein-described contrivance, the reciprocating bed is secured in the position shown in Figs. 1 and 2 of the drawings, the clothes to be washed are secured 55 to the clips 3' at one end of the roller-bed 13^a, and the crank-handle 5 is turned so as to set the belts in motion and thereby cause the clothes to be carried between the rolls of beds

13^a and 4^a and the frame 4 to be reciprocated. The result is a thorough scrubbing of the 60 clothes and removal therefrom of all dirt. The clothes are then passed through the wringer and the water thereby pressed therefrom.

What I claim is—

1. The combination of the two side stand pieces, a series of rollers journaled in said stand pieces, and having rotary motion; a longitudinally sliding frame having rollers journaled therein; bars fastened to the side 70 pieces of the frame of the stationary roller bed adjustable springs for pressing said rollers in contact with the rollers of the stationary frame, a driven roller mounted in the side pieces at the top of the first mentioned 75 series of rollers, a squeezing or wringing roller applied in connection with the said driven roller means for operating the said driven roller, and also simultaneously operating the said sliding frame, all of the said 80 parts being mounted upon the said side pieces, substantially as described.

2. The combination of the two side stand pieces, a bed of rubbing rollers journaled in said stand pieces, endless belts, carrying 85 spring clips, and passed around the bed of rubbing rollers; means for operating a roller at the top of the bed for operating the endless carrying belts; a reciprocating frame having 90 rollers journaled therein, bars fastened to the side pieces of the frame of the stationary roller means for operating said reciprocating bed frame; springs for keeping the rollers of the reciprocating frame in yielding contact 95 with the rollers of the stationary rubbing bed; all of the said parts being mounted upon the said side pieces, substantially as described.

3. The combination of the two side stand pieces; a bed of rubbing rollers journaled in the side stand pieces, the top and bottom ones 100 of which are adapted to be positively revolved, a spring acting roller above the stationary bed of rollers, endless belts provided 105 with spring clips passed around said rollers, and around the driven rollers; a reciprocating frame having rollers journaled therein, means for operating said driven rollers and the endless belts; springs for keeping the reciprocating frame in yielding contact with the rollers of the side stand pieces, substantially as described.

MARGARET KILLEEN.
